HOWARD W. FOSS, OF IRVING, NEW JERSEY.

WINDOW-CLEANING DEVICE.

1,219,282.

Specification of Letters Patent. Patented Mar. 13, 1917.

Application filed September 14, 1915. Serial No. 50,628.

To all whom it may concern:

Be it known that I, HOWARD W. Foss, a citizen of the United States, and a resident of Irving, county of Essex, and State 5 of New Jersey, have invented a certain new and useful Improvement in Window-Cleaning Devices, of which the following is a full, clear, and exact specification.

This invention relates more particularly 10 to a class of devices adapted to be used for cleaning purposes.

My invention has for its object primarily to provide a device designed to be utilized in a manner whereby window panes and 15 the like may be easily cleaned from the inside thereof instead of requiring the person doing the work to risk the danger of being injured by leaning out of the window, and which is of an adjustable as well as being of 20 an extensible form so that windows, transoms, etc., located at various heights may be conveniently cleaned. The invention consists essentially of a supporting member, or bar having in one of its ends a threaded 25 passage which is substantially T-shaped to provide a vertically disposed branch transversely therethrough as well as a communicating branch, or recess in the end of the bar, and the second end of the supporting 30 bar is slotted in a manner to provide two spaced yielding prongs on one of which are a number of teeth, or stops extending into the slot. Adapted to be removably mounted in one of the branches of the T-shaped 35 passage of the supporting bar is a rod so as to be disposed in various directions relatively to the supporting bar, and adjustably mounted on this rod is a bracket having a toothed member to permit a cloth, or wiper 40 to be detachably applied thereon.

Other objects of the invention are to provide in the slot of the supporting bar an adjustable handle, or rod having teeth, or stops coöperating with the teeth of the supporting bar for limiting the movement of the handle when in an adjusted position; to provide means for holding the teeth of the adjustable handle and the teeth of the supporting bar in releasable engagement; 50 and to provide a window cleaning device of simple, efficient and durable form.

A practical embodiment of the invention is represented in the accompanying drawing forming a part of this specification in 55 which similar characters of reference indicate corresponding parts in all the views,

the said invention being more fully described hereinafter, and then pointed out in the claims at the end of the description.

In the drawing, Figure 1 is a sectional view, partly in detail, taken vertically 60 through a window, showing one way of using my device for cleaning the panes thereof.

Fig. 2 is a detail sectional view taken 65 on the line II—II of Fig. 3.

Fig. 3 is a view of one end of the device.

Fig. 4 is a view, partly in section, taken on the line IV—IV of Fig. 3, and

Fig. 5 is a front view of the bracket used 70 in the device for holding a wiper.

The window cleaning device has a supporting member, or bar 10 which may be of any suitable length, and shape, though this bar is preferably substantially square, as 75 viewed transversely. Through one end of the supporting bar 10 is a threaded passage 11 of approximately a T-shape to provide a vertically disposed branch, as 12, and a communicating longitudinally disposed 80 branch, or recess 13 when the supporting bar is positioned in a longitudinal direction. In the second end of the supporting bar 10, and also disposed vertically therethrough, is a slot 14 which is of a length so 85 as to extend approximately to the center of the bar to provide two spaced prongs 15 and 16, the bar being made of material so that these prongs will yield sufficiently for being sprung outwardly from each other. 90 Projecting inwardly of the slot 14 from the free end part of the prong 16 are a number of ratchet-shaped teeth, or stops 17, and transversely through the prongs midway of the teeth is a threaded opening 18. 95

Adapted to be removably mounted on the supporting bar 10 is a rod 19 which may be of any desired length, and one end of this bar is threaded, at 20, so as to be detachably screwed into the threaded T- 100 shaped passage 11 of the supporting bar. When it is desired to dispose the rod 19 upwardly at a right angle with relation to the supporting bar, as shown in the drawing, the threaded end of the rod is screwed in the 105 upper end of the vertical branch 12 of the passage, and when it is desired to dispose the rod downwardly at a right angle with respect to the bar the threaded end of the rod is screwed in the lower end of the vertical passage, or when it is desired to dispose this rod longitudinally with relation 110

to the bar the threaded end of the rod is screwed into the recess 13 of the supporting bar, as illustrated in dotted lines Fig. 2.

In order to permit a wiper for cleaning the glass of a window to be carried on the adjustable rod 19, a bracket, as 21, is provided. The bracket 21 has a sleeve 22 adapted to be moved to various positions on the rod, and projecting laterally from this sleeve is an arm 23 having on its outer end a toothed member, as 24. The toothed member 24 as well as the arm 23 may be integrally formed of wire to provide the member with spaced portions on its upper and lower edges, somewhat in the fashion of teeth, or this member may be made in the form of a plate having toothed upper and lower edges, or other means may be used in conjunction with the bracket so that a cloth, or any suitable pad, as 25, for cleaning glass may be removably applied thereto. Through the sleeve 22 of the bracket 21 is a threaded orifice 26 in which is passed a set screw 27 adapted to be rotatably guided into and out of engagement with the rod 19 for tightly holding the bracket against accidental movement when adjusted on the rod.

To allow the supporting bar 10 with the rod 19 and the wiper 25 to be conveniently guided for cleaning the outside of the glass of a window so that the person manipulating the device may accomplish the work from the inside of the window, I provide an adjustable handle, or rod 28. The handle 28 may be of any desired length, and one end of the handle is formed with a flat head 29 having a threaded opening 30 centrally therethrough. The head of the handle 28 is movably disposed in the slot 14 of the supporting bar 10 so that its threaded opening 30 is in register with the threaded openings 18 through the prongs 15 and 16 of the supporting bar, and projecting from one face of the flat head of this handle are ratchet-shaped teeth, or stops 31 of a similar number to the ratchet-teeth of the prong 16 of the supporting bar. The teeth of the handle 28 are reversely shaped to the teeth 50 of the prong 16 of the supporting bar so that one set of the teeth will mesh with the other set, and serving as means to hold these sets of teeth in releasable locked engagement, through the registered threaded openings of the prongs of the supporting bar as well as through the opening of the head of the handle 30 is guided a set screw 32. When the set screw 32 is rotated accordingly the yielding prongs 15 and 16 of the supporting bar 10 will be forced against the spring action of these prongs for clamping the teeth of the handle and the prong 16 together. The handle will thereby be held against movement, and when the set screw 65 is reversely rotated the spring action of the

prongs will cause them to be sprung apart for allowing the handle to be adjusted to a desired position relatively to the supporting bar 10.

To use the device for cleaning, for instance the outside of the glass of a window, as illustrated in Fig. 1 at 33, the lower sash 34 is raised some distance, and the upper sash 35 may be lowered if desired. The handle 28 is then suitably adjusted with respect to the supporting bar 10, as above described, and the rod 19 is screwed in the upper end of the vertical branch 12 of the T-shaped passage 11 of the supporting bar so that the rod will extend upwardly. The 70 bracket 21 with the wiper applied thereto are adjusted on the rod 10 for the wiper to be guided in contact with the glass, following the disposal of the supporting bar and the rod through the window under its raised 75 lower sash. By then guiding the handle 28 in directions to move the supporting bar and the rod so that the wiper will pass in contact with various parts of the surface of the glass the window pane will be easily cleaned 80 without requiring the operator of the device to lean out of the window. Moreover, by adjusting the rod 19 and the handle 28 in various positions on the supporting bar, as 85 hereinbefore explained, windows located at 90 unusual heights may be readily cleaned by the use of my device.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to 105 make such changes as fairly fall within the scope thereof.

Having thus described my invention, I claim as new and desire to secure by Letters Patent:—

1. In a window cleaning device, a supporting bar, a rod carried by said bar and removably held by one end thereof, said bar having means by which said rod may be held in various directions relatively to the bar, 115 a bracket slidably mounted on said rod, a wiper detachably connected to said bracket, and a handle on the other end of said bar; said handle being adapted to be angularly adjusted with respect to said bar, together 120 with means for locking said handle to said bar whereby it will be held in adjusted relation.

2. In a window cleaning device, a supporting bar having a threaded substantially 125 T-shaped passage in one of its ends to provide a vertically disposed and a longitudinally disposed branch, a rod having a threaded end adapted to be screwed in any one of the branches of the T-shaped pas- 130

sage, a bracket slidably mounted on said rod, a wiper detachably connected to said bracket, and a handle on the other end of said bar; said handle being adapted to be
5 angularly adjusted with respect to said bar, together with means for locking said handle to said bar in adjusted position.

This specification signed and witnessed this thirteenth day of September, A. D. 1915.

HOWARD W. FOSS.
